UNITED STATES PATENT OFFICE.

HERBERT FLANDERS, OF MANCHESTER, NEW HAMPSHIRE.

SASH-HOLDER.

SPECIFICATION forming part of Letters Patent No. 714,569, dated November 25, 1902.

Application filed November 30, 1901. Serial No. 84,202. (No model.)

To all whom it may concern:

Be it known that I, HERBERT FLANDERS, a citizen of the United States, residing at Manchester, in the county of Hillsboro and State 5 of New Hampshire, have invented an Improvement in Sash-Holders, of which the following description, in connection with the accompanying drawings, is a specification, like characters on the drawings representing like parts.

This invention has for its object the production of a novel fastener to retain a partially-lifted sash in any desired position to thereby regulate the size of the space through 15 which air may pass.

Figure 1 in elevation shows a sash-frame and sash embodying my invention, and Fig. 2 is an inner side view of the holder detached and part of the rack-bar with which it coacts. 20 The sash-frame or window-casing A and the upper and lower sashes B C are and may be all as usual, the edges of each sash entering and sliding in usual grooves in the sash-frame or casing.

25 I apply to the sash-frame or casing at one or it may be at both sides thereof a suitable toothed rack D. One of my novel holders E is shown as applied to the right-hand side of the lower sash; but in practice I may apply 30 a like holder to the left-hand side thereof.

The holder E comprises a shell e, provided with ears e¹, having holes for the reception of screws and cast to present a projection e² and leave a chamber e³. The shell sustains 35 a stud e⁴, on which is mounted a lever e⁵, having at one end a stud e⁶. The opposite end of said lever has a curved flange e⁷, from which is extended a handle e⁸. The stud e⁶ receives on it a toothed wheel a, that engages the 40 teeth of the rack D. The lever e⁵ has a stud 2, on which is pivoted a detent-pawl a', that normally rests by its free end against the periphery of the toothed wheel a and permits said wheel to be rotated on the stud e⁶ only 45 in the direction of the arrow thereon, (see Fig. 2,) as when the window-sash is being lifted to open the window. A spring b, connected at one end with said lever e⁵ and at its other end with a stud 4 of the shell, acts 50 normally to turn said lever and keep the

toothed wheel pressed toward and so that the teeth of said wheel mesh with the teeth of the rack D.

If one lifts the sash by engaging a sash-lift c, the wheel of the holder will be rotated 55 freely by its engagement with the rack; but instantly after removing the force used to overcome the weight of the sash the slightest descent of the sash causes the end of the lever e⁵ carrying the roller to rise until the 60 back of the detent a' meets the stud 4, and as the roller then sustaining the weight of the sash is restrained from rotation by the detent in a direction opposite the arrow, Fig. 2, it follows that the sash may be left open 65 at any point, that depending upon the quantity of air-space desired.

To lower the sash, one will engage the end e⁸ of the lever and turn it about the stud e⁴ far enough to disengage the teeth of the 70 wheel from the teeth of the rack, and thereafter the sash is free to descend.

With this holder the sash is always in condition to be raised; but it cannot be lowered except by moving the lever by the finger-piece e⁸. 75

The holder is very desirable for use in cars and preferably two holders will be applied to each sash, and, if desired, the sash may be lifted by engaging directly and lifting on the 80 ends e⁸ of the levers. The wall e⁷ substantially closes the gap in the side wall of the shell, thus adding to the neat appearance of the holder.

Having described my invention, what I 85 claim as new, and desire to secure by Letters Patent, is—

1. In a sash-holder, a shell having a chamber and adapted to be secured to a sash, a lever pivoted on said shell and having at one 90 end a thumb-piece and sustaining at its opposite end a toothed wheel, a detent to prevent the rotation of said wheel in one direction as when sustaining the weight of a sash.

2. In a sash-holder, a shell having a chamber and adapted to be secured to a sash, a lever pivoted on said shell and having at one 95 end a thumb-piece and sustaining at its opposite end a toothed wheel, a detent to prevent the rotation of said wheel in one direction.

tion as when sustaining the weight of a sash, and a spring acting normally to elevate the end of said lever carrying said toothed wheel.

3. In a sash-holder, a shell having a chamber and adapted to be secured to a sash, a lever pivoted on said shell and having at one end a thumb-piece and sustaining at its opposite end a toothed wheel, a detent to prevent the rotation of said wheel in one direction, as when sustaining the weight of a sash, a spring acting normally to elevate the end of said lever carrying said toothed wheel, and

means against which the detent is forced when the wheel and lever sustain the weight of a sash to thereby hold the detent firmly in engagement with said wheel to prevent it from being rotated by the weight of the sash.

In testimony whereof I have signed my name to this specification in the presence of two subscribing witnesses.

HERBERT FLANDERS.
